UNITED STATES PATENT OFFICE.

MATTHEW M. PITTMAN, OF FINDLAY, OHIO.

CAR-COUPING.

SPECIFICATION forming part of Letters Patent No. 352,349, dated November 9, 1886.

Application filed July 19, 1886. Serial No. 208,403. (No model.)

To all whom it may concern:

Be it known that I, MATTHEW M. PITTMAN, a citizen of the United States, and a resident of Findlay, in the county of Hancock and State of Ohio, have invented certain new and useful Improvements in Car-Couplings; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved coupling. Fig. 2 is a cross-section through the line *x x*, Fig. 1. Fig. 3 is a horizontal section on the line *y y*, Fig. 2; and Fig. 4 is a detail view of the arrow-head bolt.

Similar letters of reference indicate corresponding parts in all the figures.

My invention has relation to car-couplings; and it consists in the improved construction and combination of parts of the same, as hereinafter more fully described and claimed.

25 In the accompanying drawings, the letter A represents the draw-head, having the side B thereof recessed on its inner face, and provided with flaring outer end, C, and also having disposed therein and secured to the rear thereof a spring, D, conforming to the shape of said inner face. This spring D, when pressure is exerted upon the same, is adapted to fit in a longitudinal groove, b, which terminates in a notch, c, located in the shoulder to the rear of 35 the flaring outer end, C, and into which also the free end of the spring fits when said spring is subjected to pressure. The opposite side of the draw-head consists of a pivoted jaw, E, of the same shape as the rigid jaw, being also 40 provided with flaring hook-shaped outer end, F, having notch f to the rear thereof, and a spring suitably secured to its inner face and adapted to fit in a similar longitudinal groove, e. A sliding lock or key, G, working in grooves 45 or ways H in the draw-head, extends laterally from said draw-head, and by means of a suitable gearing mechanism, hereinafter referred to, serves to regulate the operation of the pivoted jaw in coupling and uncoupling the cars. 50 The upper side of this sliding lock G is grooved

longitudinally, and has arranged therein a series of cogs, I, and it is also provided on one end with a removable stop or button, J.

Working in a suitable bearing, K, secured to the top of the draw-head is a transverse shaft, L; having shoulder or step M at one end and a cog wheel, N, on the opposite side of the bearing, said cog-wheel being integral therewith. The teeth of this wheel N mesh with the cogs I of the sliding lock G, and by 60 means of a lever, O, said sliding lock may be operated from the platform of the car, or may be operated from either side thereof, the two ends of the transverse shaft being beveled or smoothed off, so as to afford a firm grasp when 65 the coupling or uncoupling is effected in this manner.

P represents the arrow-head bolt, which is a substitute for the usual link, and is provided with a transverse shoulder, Q, at its central 70 portion, which bears against the mouth-piece of the draw-head when the bolt is in position.

When it is desired to couple cars by means of my invention, the sliding lock or key is moved backward until one of the cogs of the 75 transverse shaft comes in contact with the removable stop or button J, at which position the pivoted jaw is free to admit of the entrance of the arrow-head bolt P. As the end of the bolt enters the draw-head the lever is moved 80 backward, which simultaneously brings the sliding lock forward until it comes in contact with a laterally-extending shoulder, R, on the pivoted jaw E, the arrow-head bolt being 85 grasped securely between the pair of jaws B E.

To uncouple the cars the reverse operation is necessary. When the sliding lock is moved backward as far as possible, the downward pressure on the pivoted jaw is relieved, and the lower spring, acting upon the bolt P, causes 90 a pressure to be exerted upon the upper spring, and, releasing the pivoted jaw, throws the same out of engagement with the arrow-head bolt, which readily admits of the withdrawal of the same.

From the foregoing description, taken in connection with the accompanying drawings, the operation and advantages of my improvement will be easily understood without requiring further explanation.

Having thus described my invention, I claim and desire to secure by Letters Patent of the United States—

1. In a car-coupling, the combination of the rigid jaw having its inner face recessed and provided with a hook shaped outer end, the spring secured in the rear of said rigid jaw, the pivoted jaw having a corresponding recess and hook-shaped outer end, the spring secured to in the rear of said pivoted jaw, and means, substantially as described, for locking and unlocking the pivoted jaw.

2. In a car-coupling, the combination of the rigid jaw having its inner face recessed and provided with a longitudinal groove and hook-shaped outer end, the spring secured in said groove, the pivoted jaw having a corresponding recess, groove, and hook-shaped outer end, the spring secured in said groove, and means, substantially as described, for locking and unlocking the pivoted jaw.

3. In a car coupling, the combination of the rigid jaw having hook shaped outer end, the pivoted jaw having corresponding hook-shaped outer end, the sliding lock or key having a series of cogs on the upper side thereof, the transverse shaft having a step or shoulder at one end, and the other end being provided with a cog-wheel, and lever for operating the sliding lock.

4. In a car-coupling, the combination of the rigid jaw having hook-shaped outer end, the pivoted jaw having corresponding hook-shaped outer end, the outer face of said end being provided with a laterally-extending flange or shoulder, the sliding lock or key having a series of cogs on the upper side thereof, the transverse shaft having its ends beveled, one of said ends having a step or enlargement, and the opposite end being provided with a cog-wheel, and lever for operating the sliding lock.

5. In a car coupling, the combination of the rigid jaw having hook-shaped outer end, the pivoted jaw having corresponding hook-shaped end, the outer face of said end being provided with a laterally-extending flange or shoulder, the sliding lock or key having a series of teeth or cogs and a removable stop or button, the transverse shaft having its ends beveled, one of said ends having a step or enlargement, and the opposite end being provided with a cog-wheel, and a lever for operating the sliding lock.

In testimony that I claim the foregoing as my own I have hereunto affixed my signature in presence of two witnesses.

MATTHEW M. PITTMAN.
